(57) **CLAIM**

The ornamental design for a tire inner tube as shown and described.

DESCRIPTION

FIG. 1 is a perspective view of a tire inner tube showing my new design;

FIG. 2 is a left elevational view thereof;

FIG. 3 is a right elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a cross-sectional view thereof taken along line 8-8 of FIG. 3, shown in an environment of use.

The portions of the drawing in broken lines show an environment of use and form no part of the claimed design.

1 Claim, 5 Drawing Sheets
